United States Patent Office.

T. S. LA FRANCE, OF ELMIRA, NEW YORK.

Letters Patent No. 98,697, dated January 11, 1870.

IMPROVEMENT IN SAFETY-VALVES.

The Schedule referred to in these Letters Patent and making part of the same.

To all whom it may concern:

Be it known that I, T. S. LA FRANCE, of Elmira, in the county of Chemung, and State of New York, have invented a new and improved Safety-Valve; and I do hereby declare that the following is a full, clear, and exact description thereof, which will enable others skilled in the art to make and use the same, reference being had to the accompanying drawing, forming part of this specification.

The drawing represents a vertical central section of my improved safety-valve.

This invention relates to a new safety-valve for steam-boilers, and has for its object to adapt the valve to any desired degree of steam-pressure, so that it will be opened by the steam whenever the same will reach the said degree of pressure, and that it can also be raised off the seat by a separate apparatus, whenever steam is to be blown off.

The invention consists in a novel combination, with the valve and valve-rod, of an elevating screw-cap, as hereinafter more fully described.

A, in the drawing, represents a vertical pipe, in which the annular valve-seat *a*, for supporting the valve, is arranged.

B is the safety-valve. It is held down upon the seat by a spiral spring, *b*, which is fitted around the valve-stem *c*, between the valve and a tubular screw, *C*, which is held in the top plate or head *d* of the pipe *A*.

The valve-stem fits through the bore of the screw *C*, and can play up and down therein.

Above the head *d* are formed, on the screw *C*, pro-

jecting handles, *e e*, by means of which the screw can be turned to lower or raise it in the head, and to thereby compress the spring to a greater or lesser degree. The valve is thus held upon its seat by the spring-pressure, which can be varied at will, in order to adapt the device to greater or lesser steam-pressure.

When the pressure exceeds the spring-power, the valve will be raised, and the steam will pass into the upper part of the tube, whence it escapes through suitable apertures, *f*.

Below the valve is, screwed into the lower part of the pipe *A*, a shaft, *D*, which, with its upper end, fits against the under side of the valve, or against the end of a rod, *g*, projecting downward from the same.

By turning a hand-wheel, *h*, at the lower end of the shaft *D*, the latter can be screwed up to raise the valve off the seat, whenever it is desired to blow off the steam in the boiler.

Steam enters the pipe *A* through a pipe, *i*.

Having thus described my invention,

I claim as new, and desire to secure by Letters Patent—

The safety-valve *B*, arranged in the pipe *A*, and combined with the spring *b* and screw *C*, and with the lower screw-shaft *D*, substantially as described, to operate as set forth.

The above specification of my invention signed by me, this 11th day of November, 1869.

T. S. LA FRANCE.
